(57) **CLAIM**

The ornamental design for a soda can organizer, as shown and described.

DESCRIPTION

FIG. 1 is a front and top perspective view of a first piece of a soda can organizer, shown separately for completeness of illustration;

FIG. 2 is a rear and top perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof;

FIG. 8 is a bottom plan view thereof;

FIG. 9 is a front and top perspective view of a second piece of the soda can organizer, shown separately for completeness of illustration;

FIG. 10 is a front and bottom perspective view thereof;

FIG. 11 is a front elevation view thereof;

FIG. 12 is a rear elevation view thereof;

FIG. 13 is a left side elevation view thereof;

FIG. 14 is a right side elevation view thereof;

FIG. 15 is a top plan view thereof;

FIG. 16 is a bottom plan view thereof;

FIG. 17 is a front and top perspective view of the soda can organizer;

FIG. 18 is an exploded view thereof;

FIG. 19 is a front and bottom perspective view of FIG. 18; and,

FIG. 20 is an enlarged view of detail '20' identified in FIG. 10.

The broken lines in the figures illustrate portions of the soda can organizer that form no part of the claimed design. The dash dot dash lines in FIGS. 10 and 20 are for the purpose of illustrating the enlarged view indicators and form no part of the claimed design.

1 Claim, 20 Drawing Sheets
